William E. Harris, Cincinnati, Ohio, assignor of
one-half to John D. Powell, Cincinnati, Ohio

Application May 21, 1938, Serial No. 77,325

Term of patent 14 years

To all whom it may concern:

Be it known that I, William E. Harris, a citizen of the United States, residing at Cincinnati, in the county of Hamilton and State of Ohio, have invented a new, original, and ornamental Design for a Measuring Instrument, of which the following is a specification, reference being had to the accompanying drawing, forming a part thereof.

Fig. 1 is a perspective view of the measuring instrument showing my new design;

Fig. 2 is a top plan view thereof;

Fig. 3 is a side elevation.

I claim:

The ornamental design for a measuring instrument, as shown.

WILLIAM H. HARRIS.
